US00D975750S

(12) **United States Design Patent** (10) **Patent No.:** **US D975,750 S**
(45) **Date of Patent:** **** Jan. 17, 2023**

(54) **PUMP ASSEMBLY**

(71) Applicants: **Hans L. Kuster**, Barrington, RI (US);
Michael McNamara, Coventry, RI (US)

(72) Inventors: **Hans L. Kuster**, Barrington, RI (US);
Michael McNamara, Coventry, RI (US)

(73) Assignee: **AquaMotion, Inc.**, Barrington, RI (US)

(***) Term: **15 Years**

(21) Appl. No.: **29/842,499**

(22) Filed: **Jun. 14, 2022**

Related U.S. Application Data

(60) Continuation of application No. 29/837,204, filed on May 3, 2022, and a continuation of application No. 29/832,058, filed on Mar. 24, 2022, and a continuation of application No. 29/829,955, filed on Mar. 9, 2022, now Pat. No. Des. 960,202, which is a division of application No. 29/754,904, filed on Oct. 15, 2020, now Pat. No. Des. 949,927.

(57) **CLAIM**

The ornamental design for a pump assembly, as shown and described.

DESCRIPTION

FIG. 1 is a perspective view of a pump assembly;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines shown in the drawing views are included for the purpose of showing environmental structure that forms no part of the claimed design.

1 Claim, 7 Drawing Sheets
